(57) **CLAIM**

The ornamental design for a controller for shoulder strap for bags, as shown and described.

DESCRIPTION

FIG. 1 is a perspective view of a controller for shoulder strap for bags;

FIG. 2 is a front view of the controller for shoulder strap for bags of FIG. 1;

FIG. 3 is a rear view of the controller for shoulder strap for bags of FIG. 1;

FIG. 4 is a left side view of the controller for shoulder strap for bags of FIG. 1;

FIG. 5 is a right side view of the controller for shoulder strap for bags of FIG. 1;

FIG. 6 is a top view of the controller for shoulder strap for bags of FIG. 1;

FIG. 7 is a bottom view of the controller for shoulder strap for bags of FIG. 1; and,

FIG. 8 shows a perspective view of the controller for shoulder strap for bags of FIG. 1 holding a belt connected by being placed on one of backpack straps.

The broken lines illustrate environment and form no part of the claimed design.

1 Claim, 8 Drawing Sheets
